GAME BOARD OR SIMILAR ARTICLE

Roger Price, New York, N.Y., assignor to Random House,
Incorporated, a corporation of New York

Filed Aug. 29, 1968, Ser. No. 13,314

Term of patent 14 years

Int. Cl. D21—01

U.S. Cl. D34—5

The figure is a plan view of the game board or similar article embodying my new design.

The crosshatchings in the figure indicate contrasting colors.

The game board or similar article is of conventional thickness.

I claim:

The ornamental design for a game board or similar article, substantially as shown and described.
